UNITED STATES PATENT OFFICE.

CHARLES A. LINDSTRÖM, OF PITTSBURGH, PENNSYLVANIA, ASSIGNOR TO PRESSED STEEL CAR COMPANY, OF PITTSBURGH, PENNSYLVANIA, A CORPORATION OF NEW JERSEY.

CAR CONSTRUCTION.

1,173,526.

Specification of Letters Patent. Patented Feb. 29, 1916.

Application filed October 25, 1912. Serial No. 727,737.

To all whom it may concern:

Be it known that I, CHARLES A. LINDSTRÖM, a citizen of the United States, residing at No. 138 Stratford avenue, Pittsburgh, 5 E. E., in the county of Allegheny and State of Pennsylvania, have invented certain new and useful Improvements in Car Construction, of which the following is a full, clear, and exact description of the same, reference 10 being had to the accompanying drawings, in which like characters refer to like parts, and in which—

Figure 1 is a plan view of substantially one-half of a general car embodying my invention. Fig. 2 is a transverse section of the car, the left-hand half of the figure being taken on the line A—A of Fig. 1, and the right-hand half on line B—B of Fig. 1. Figs. 3, 4 and 5 inclusive are side elevations 20 of intermediate portions of the side of the car, and Figs. 6, 7 and 8 inclusive are sections on line C—C of Figs. 3, 4 and 5 respectively. Figs. 9 and 10 are side elevations of the end portions of the side of the car and Figs. 11 and 12 are sections on line D—D of Figs. 9 and 10. Fig. 13 is a horizontal section on line E—E of Fig. 10, and Figs. 14 and 15 are horizontal sections on line F—F of Figs. 4 and 5 respectively. 25 Fig. 16 is an end elevation of the car, and Figs. 17 and 18 are horizontal sections showing modifications in the form and construction of the side stakes.

My invention relates to car construction 35 and mechanism especially adapted for carrying ordinary freight, as well as for ladings which it may be desirable to dump through the bottom of the car, when standing on trestles or on the usual level track; though 40 it is adaptable for use with any suitable type of car doors and operating mechanism.

An object of the present invention is to provide a simple, strong and economical construction of car, especially adapted for 45 that class of freight cars having drop bottoms and known in the trade as general service cars, but which may also be applied to gondola and other freight cars without drop bottoms.

50 Another object of the present invention is to provide a car having a stronger side construction than has hitherto been possible, which object is attained by the novel form

of side stake employed, having its greatest cross section at the portion which is subjected to the greatest bending moment, namely, its lower end portion.

Another object of this invention is to construct the side stakes of such a form that the lower portions thereof will constitute substantial supports for the inclined load carrying floor plates, which rest upon and are secured thereto, and form a protection to the door winding shaft against damage from the lading while being discharged.

Another object of this invention is to eliminate the inside gusset plates, which have hitherto been necessary to give the sides of the car the necessary amount of lateral stiffness to resist the thrust of the 70 lading, which object is also attained by the novel form of side stake heretofore referred to, and resulting in a car which has no internal obstructions in the form of gusset plates to interfere with the lading.

Another object of this invention is to utilize what has, in cars constructed hitherto, been left as a vacant space, formed by the side stakes, the inclined load carrying floor plates and the end portions of the transoms, 80 but which in my construction is partly occupied by the lower widened portion of the novel form of side stake herein described.

Another object of this invention is to support the door winding and locking shaft in 85 the lower portion of the side stakes, thus obviating any perforation or cutting away of portions of the transoms, with its resultant weakening effect.

Another object of this invention is to construct a car which in the event of its sides being damaged by side swipes or other accidents, can be more readily and cheaply repaired by removing and replacing where necessary, the side stakes and sides, without 90 interfering with the transoms, which in cars at present constructed extend to and are secured to the sides of the car, and which in the event of damage to the side of the car, are usually also damaged and require to be 100 either replaced or removed for repairs, necessitating an almost complete dismantling of the car underframe.

A further object of this invention is to support the door winding and locking shaft 105 in such a manner that it can be easily re-

5 moved from its supports in a downward direction, by supporting it in openings provided in the lower portion of the side stakes, thus avoiding the making of such openings in the ends of the transoms, as has been customary heretofore.

A further object of this invention is to provide certain modifications of the hereinbefore described structures.

10 More specifically stated my invention relates to that class of car and door operating and latching mechanism which is illustrated, described and claimed in United States Letters Patent No. 791,348, granted May 30th, 1905 to myself and John F. Streib and United States Letters Patent No. 833,402, granted October 16th, 1906 to me. In the mechanism of both of these patents, chain means is employed for raising the doors, and 15 20 a creeping shaft is employed for first winding said chain means and then latching the doors in raised position directly on the shaft and not through the medium of the chain means, to relieve the chain means from load 25 strains. It is however to be understood that my invention may be applied to bottom dump cars having door operating mechanism of other types than that above referred to, and which are provided with door operating shafts extending longitudinally of 30 the car and at or near the vertical plane of the car sides.

Referring now in detail to the drawings, 1 indicates the center sill of the car which may 35 be of any suitable form, such as box girder or I beam, but preferably of the modified A-shape illustrated in Fig. 2 of the drawings. This form of center sill is fully illustrated, described and claimed in United 40 States Letters Patent No. 833,402, granted to me October 16th, 1906, and hence it is unnecessary to describe it in further detail in this specification.

2 indicates the body bolster which may 45 also be constructed of any preferred form, but which is illustrated in the drawings as being constructed in two sections, of plates and angle irons and secured at its inner end to the center sill. The outer ends 3 of these 50 bolster members do not extend, as has been the usual practice, to the vertical plane of the side of the car, nor are they secured thereto, but terminate some distance therefrom. These bolster members are furnished 55 with the usual top tie plate 4 extending across the center sill, and bottom tie plate 5, as well as the usual center bearing plate 6 and side bearing members 7.

8 indicates the transoms of the under- 60 frame which are preferably constructed of steel plates pressed into shape and having integral flanges. These transoms are of a length substantially equal to the length of the bolster members, that is to say, they do 65 not extend from the center sills to which

they are secured, to the vertical plane of the car side, but are stopped short at a suitable distance therefrom. These transoms are provided with top flanges 9, end flanges 10 which are secured to the center sill, bottom 70 flanges 11 which are deflected downwardly to prevent the discharging lading from lodging thereon, and outer end flanges 12 to which the lower end portions of the side stakes are secured. These transoms may 75 also be provided with brackets 13 of triangular or other suitable shape which are secured to the lower flanges of the transoms and to the lower portions of the center sill, and which serve to brace and strengthen the 80 connections of the transom to the center sill.

14 indicates the novel form of side stakes with which the car is furnished and which are preferably formed of plates pressed into the form of a Z, having a varying cross 85 section from end to end and a lower end portion adapted to be secured to the ends of the transoms. The side stakes 14 which are secured to the bolsters as well as those secured to the transoms adjacent to the bolsters are of similar construction to the other side stakes, but are provided with an additional angle bar reinforcing member 15, which is secured to the stake, to the sides 90 and sloping floor of the car, and to the ends 95 of the bolster members. These stakes are all constructed in such a form as to provide an inwardly sloping portion 16 and an end portion 17 of greatly increased horizontal depth as compared with the upper portion 18, thus providing greatly increased strength in the side stake at the point where the bending moment is greatest due to the sidewise thrust of the lading.

19 indicates the side wall of the car, the upper portion 20 of which is substantially vertical, the lower portion 21 sloping inwardly and downwardly and forming an inclined load carrying floor plate. The lower portion 22 is also bent outwardly toward the side of the car forming a longitudinal edge plate, which is notched or cut away to permit the lower portion of the side stakes to pass therethrough. The top tie plate member 4 of the bolster, which as previously stated extends across the center sill of the car, also extends to and has its outer ends 23, 23 bent upward in such a manner as to contact with the lower portions of the inclined load carrying floor plates 21 and said ends are secured thereto. The upper tie plate members 24 of the transoms 8 do not extend continuously across the center sill but their inner ends lap under the top flange 25 of the T-shaped upper member 26 of the center sill, and are secured thereto. The outer ends 27 of these tie plate members extend to the inclined load carrying floor plates 21, and have their ends inclined upwardly to contact therewith and are se- 120 125 130

cured thereto in a manner similar to that described in connection with the bolster tie plates.

The lower portions 17 of the side stakes are provided with flanges 28 which are secured to the end flanges 12 of the transoms 8 and to the outer ends 3 of the bolster members. The lower portions 17 of the side stakes are perforated at 29, and provided with casting members 30 which are secured thereto, and in which slots 31 are formed to permit of the application and support of the door winding and latching shaft 32, but as this mechanism is fully illustrated, described and claimed in United States Letters Patent No. 791,348, granted May 30th, 1905, to myself and John F. Streib, further description of the same is herein considered unnecessary. The castings 30 are provided with openings 33 in their lower portions to permit of the removal of the shaft 32 for the purpose of repair or replacement, the openings 33 in the castings 30 being furnished with a removable member 34 adapted to be secured therein, the withdrawal of which permits the shaft with all its accessories to be lowered bodily from its normal position in the slot 31 in the casting 30. However, as this feature is fully illustrated, described and claimed in United States Letters Patent No. 993,082, granted to me May 23rd, 1911, further description of the same is herein considered unnecessary.

The drop doors 35 are hinged to the center sill in the usual manner and the bolster members and transoms adjacent to the doors are provided with suitable stop members 36 to prevent the dropping of the doors more than a predetermined distance.

Fig. 17 shows a modification of the construction of the side stake of the car, in which the body member of the stake is formed of a steel plate pressed into channel form of varying section and reinforced by an angle bar riveted to the back of the inner edge of the stake member. Fig. 18 illustrates a further modified form of the construction of the side stake of the car, in which the stake is formed of a steel plate pressed into channel form of varying cross section.

Within the scope of my invention, as defined in the claims, the construction of the parts may be modified in many ways by the skilled mechanic, since, what I claim is:—

1. In a railway car, a metallic side stake having a substantially vertical upper portion, an enlarged inwardly sloping intermediate portion and an enlarged lower portion.
2. In a railway car, a metallic side stake having a substantially vertical upper portion and an enlarged inwardly and downwardly sloping intermediate portion and an enlarged lower portion.
3. In a railway car, a metallic side stake

made of one piece having a substantially vertical upper portion, an enlarged inwardly sloping intermediate portion and an enlarged lower portion.

4. In a railway car, a metallic side stake made of one piece having a substantially vertical upper portion, an enlarged inwardly and downwardly sloping intermediate portion and an enlarged lower portion.

5. In a railway car, a metallic side stake having a substantially vertical outer surface, a substantially vertical upper inner surface, an intermediate inwardly sloping inner surface and a substantially vertical lower inner surface.

6. In a railway car, a metallic side stake having a substantially vertical outer surface, a substantially vertical upper inner surface, an intermediate inwardly and downwardly sloping inner surface and a substantially vertical lower inner surface.

7. In a railway car, a metallic side stake having a substantially vertical upper portion, and enlarged inwardly sloping intermediate portion and an enlarged lower portion, said lower portion being provided with a perforation for the reception of door latching mechanism.

8. In a railway car, a metallic side stake having a substantially vertical upper portion and an enlarged inwardly sloping intermediate portion and an enlarged lower portion, in combination with door latching mechanism supported in perforations formed in said enlarged lower portion.

9. In a railway car, a metallic side stake made of one piece having a substantially vertical upper portion, an enlarged inwardly sloping intermediate portion and an enlarged lower portion in combination with door latching mechanism supported in said enlarged lower portion.

10. In a railway car, a metallic side stake made of one piece having a substantially vertical upper portion, an enlarged inwardly sloping intermediate portion and an enlarged lower portion provided with a perforation therethrough in combination with a door latching mechanism supported in said perforation.

11. In a railway car, the combination with the transoms, of a side, a sloping floor and a side stake adapted to support said side and sloping floor, and secured to said transoms.

12. In a railway car, the combination with the transoms, of a side, an inwardly and downwardly sloping floor and a side stake adapted to support said side and sloping floor and secured to said transoms.

13. In a railway car, the combination with the transoms and a sloping floor, of metallic side stakes extending under and adapted to support said sloping floor and secured to said transoms.

14. In a railway car, the combination with the bolsters and sloping floor, of metallic side stakes extending under and adapted to support said sloping floor and secured to said bolsters.
15. In a railway car, the combination with an underframe comprising center sills, body bolsters and transoms, of a car side and sloping floor, said car side and sloping floor being supported by side stakes extending under said sloping floor and secured to said transoms.
16. In a railway car, the combination with an underframe comprising center sills, body bolsters and transoms, of a car side and sloping floor, said car side and sloping floor being supported by side stakes extending under said sloping floor, and secured to said bolsters.
17. In a railway car, the combination with an underframe, comprising center sills, body bolsters and transoms, of a car side and sloping floor, said car side and sloping floor being supported by side stakes extending under said sloping floor, and secured to said bolsters and transoms.
18. In a dump car, the combination with the center sills, bolsters, transoms, side, sloping floor and side stakes, of door supporting mechanism supported in said side stakes.
19. In a dump car, the combination with center sills, bolsters, transoms, side, sloping floor and side stakes, of door supporting mechanism supported by said side stakes.
20. In a dump car, the combination with a center sill, of bolsters and transoms terminating inside the vertical plane of the car side, of side stakes secured to said car sides having enlarged lower portions adapted to meet and be secured to the ends of said bolsters and transoms.
21. In a dump car, the combination with the car sides, sloping floor, drop-doors and door supporting shaft, of a side stake adapted to support said side and sloping floor, and having openings therein for the reception of the door supporting shaft.
22. In a railway car, the combination with a center sill having a T section upper member, of transoms secured to said sill, and transverse tie plates secured to the under side of the horizontal flanges of said T section, and secured to said transoms.
23. In a railway car, the combination with a center sill having a T section upper member, transoms secured to said sill, and a sloping floor plate, of transverse tie plates secured to the under side of the horizontal flanges of said T section, and to said transoms and sloping floor plates.
24. In a railway car, the combination with a center sill having a T section upper member, transoms secured to said sill, and an inwardly and downwardly sloping floor plate, of transverse tie plates lapping under and secured to the horizontal flanges of said T section upper member, and to said transoms and inwardly and downwardly sloping floor plate.
25. In a railway car, the combination with a center sill, of a side wall, transversely extending members secured to said center sill terminating within the vertical plane of said side wall and a vertically disposed member secured to said side wall and transverse members, said members having substantially vertical upper portions, enlarged inwardly sloping intermediate portions and enlarged lower portions.
26. In a railway car, the combination with a center sill, of a side wall having vertical and inclined portions, transversely extending members secured to said center sill and terminating within the vertical plane of said side wall, and stakes secured to said side wall and transverse members, said stakes having a substantially vertical upper portion and an enlarged lower portion.
27. In a railway car, the combination with a center sill, of a side wall, a transversely extending member secured to said center sill and terminating within the vertical plane of said side wall, a vertically disposed member secured to said side wall and transverse member, said member having a substantially vertical upper portion and an enlarged lower portion and a strengthening member secured to said vertically disposed member.
28. In a railway car, the combination with a center sill, of a side wall having vertical and inclined portions, transversely extending members secured to said center sill, said transverse members terminating within the vertical plane of said side wall, and stakes secured to the inner edge portions of said transverse members and side wall, said stakes conforming to the shape of said side wall, and the outer edge portions of said stakes being in substantially the same vertical plane throughout the length of said stakes.
29. In a railway car, the combination with a center sill, of a side wall, having a vertical upper portion and an inclined lower portion, a vertical stiffening member secured to said side wall, said member having an enlarged inwardly extending lower portion, and a transverse member secured to said center sill and to the lower portion of said vertical stiffening member within the vertical plane of said side wall.
30. In a railway car, the combination with a center sill, of a transverse member secured to said center sill, a drop door adjacent said transverse member, a side wall, a stake secured to said side wall, said stake

having an enlarged lower portion secured to said transverse member, a substantial distance within the vertical plane of said side wall, and means mounted in said stake for operating said door.

5 31. In a railway car, the combination with the side wall having a vertical upper portion and an inwardly sloping lower portion, a side stake having a substantially vertical outer surface and an inner surface conforming to the shape of said side wall, and means for securing said side wall and stake together.

10 32. In a railway car, the combination with a center sill of a side wall having vertical and inclined portions, a transom secured to said center sill and terminating a substantial distance short of the vertical plane of the vertical portion of said side wall, and a 20 vertical stake having an enlarged lower portion extending inwardly beyond the vertical plane of the vertical portion of said side wall and secured to said transom, and means for securing said side wall to said stake.

25 33. In a railway car, the combination with a side wall, of a vertical member of greater length than the height of said side wall, means mounted within and passing through said vertical member adapted to directly 30 support dump doors, said means being in a plane below said doors and means for securing said vertical member to said side wall.

35 34. In a railway car, the combination with the underframe of a side wall, a vertical stake member secured to said side wall and underframe, said vertical member having a slotted opening for the reception of a door supporting mechanism, and a removable member carried by said stake adapted to define a portion of said opening.

40 35. In a railway car, the combination with a center sill of transverse members secured thereto, side walls having vertical and inclined portions, vertical members secured to said vertical and inclined portions, said vertical members varying in cross section, bearing members secured to said vertical members, a bodily movable door operating 50 shaft mounted in said bearing members, and means for securing said vertical members to said transverse members.

45 36. In a railway car, the combination with the sides, of a center sill, transoms secured to said sill and terminating a substantial distance within the planes of said sides, and stakes adapted to connect said sides and transoms, said stakes each having an enlarged inwardly extending lower portion secured to one of said transoms.

50 37. In a railway car, the combination with the side wall plates, of a center sill, transoms connected with said sill and terminating a substantial distance within the vertical planes of said plates, sloping floor plates se-

cured to the first mentioned plates and stakes connecting said plates and transoms, said stakes having enlarged inwardly extending lower portions secured to said transoms.

38. In a railway car, the combination with a side wall having vertical and inclined portions of a Z-shaped stake having an outer flange in substantially the same vertical plane throughout its length and an inner flange having vertical and sloping portions 75 and means for securing said inner flange to the vertical and inclined portions of said wall.

39. In a railway car, the combination with the side walls of a center sill, transverse 80 members connected with said sill and terminating a substantial distance within the planes of said walls and Z-shaped strengthening members secured to said members and walls, said members having enlarged lower 85 portions.

40. In a dump car, the combination with the center sill, of transverse members secured thereto, a side wall having vertical and inclined portions, stakes secured to said side wall and transverse members, and bodily movable door raising mechanism mounted in said stakes.

41. In a dump car, the combination with the center sill of a side wall having an inclined floor portion, transverse members secured to said center sill, vertically disposed strengthening members secured to said transverse members and adapted to support said inclined floor portion, and bodily movable 100 door raising means mounted in said stakes.

42. In a dump car, the combination with a side wall of a vertically disposed stake member adapted to brace said wall, a door and bodily movable door operating means 105 mounted in said member below said side wall adapted to move under and support said door.

43. In a dump car, the combination with a side wall, of a vertically disposed stake member arranged to brace said wall, a bodily movable shaft mounted in said member, and door supporting rollers mounted on said shaft, said shaft and rollers being bodily removable from said member.

44. In a dump car, the combination with a side wall of a vertically disposed stake member arranged to brace said wall and having an opening for the reception of a bodily movable discharge door operating 120 shaft, a side portion of said opening being removable.

45. In a dump car, the combination with a side wall, of a stake adapted to brace said wall and having a shaft guide slot formed therein, an opening in the lower side of said slot, and a removable filling piece in said opening.

46. In a dump car, a side stake having a 125 guide slot for a shaft formed therein, an 130

opening in a side of said slot, and removable means for closing said opening.

47. In a car, the combination with a side wall having vertical and inclined portions of a Z-shaped stake arranged to brace said wall and an L-shaped member secured to said wall and stake, said stake having an enlarged lower portion extending inwardly beyond the vertical plane of the vertical portion of said side wall.

48. In a dump car, the combination with a side wall having vertical and inclined por-

tions, a webbed stake arranged to brace said wall and a strengthening member secured to said vertical and inclined portions and to the web of said stake, said stake having an inwardly extending enlarged lower portion.

In testimony whereof I affix my signature in presence of two witnesses.

CHARLES A. LINDSTRÖM.

Witnesses:

FRANK E. MILLER,
MARGARET SUMMERBELL.
